DETACHABLE COLLAR

Salvatore Lapick, Lakewood, Ohio, assignor to
 The Printz-Biederman Company, a corporation
 of Ohio

Application April 11, 1942, Serial No. 438,595

4 Claims. (Cl. 2-98)

This invention relates to improvements in detachable collars particularly for use with garments worn by women and young ladies.

More particularly, my invention provides for an arrangement for detachably removing a collar, such as a fur collar, so that the garment with the detachable collar removed gives a finished appearance.

A further object of my invention is to provide an easy and simple means for attaching a fur collar to a cloth garment so that the attached fur collar looks as though it were actually permanently attached to the outer garment.

Another object of my invention is to provide simple means for interchanging different collars, such as different fur collars and cloth collars for use upon a cloth coat.

In order to take care of differences in weather and for different occasions where one type of collar may be more suitable than another, my invention provides for a ready, inexpensive, easy and quick means for interchanging such collars.

Another important object of my invention is to provide a construction where the means for attaching the collar to the body of the garment are concealed when the garment is worn by a person.

These and other advantages will become apparent from the following detailed description taken in connection with the accompanying drawing, wherein:

Fig. 1 is a perspective view of the upper part of the front of the garment with one end of the collar raised to show the features embodying my invention.

Fig. 2 is an inside view of the upper portion of the coat shown in Fig. 1, showing the construction for attaching a collar.

Fig. 3 is a plan view of the back of a fur collar showing the means used for attachment to a coat.

Fig. 4 is a section taken through line 4-4 of Fig. 1.

Referring to the drawing, numeral 10 represents an outer garment or coat which can be made of any desirable material and used either for children, juniors, misses, women's and men's coats, jackets and suits of almost any type and description. Such outer garment may be lined or unlined depending upon the type of garment and the cost of manufacture. Outer garment 10 has attached to the yoke 11 a short collar 12 by stitching 13. A series of openings 14 are placed at predetermined distances between yoke 11 and the short collar 12. Such openings 14 may be of any desired number. Below each opening 14

and at a predetermined distance from such opening there is attached to the inside of the yoke 11 one part of a snap fastener 15.

5 A fur collar 16 has a backing material 17 which may be of any desired material stitched to the inside of the fur collar by stitching 18. Tabs 19 are attached to the neck portion of the backing material 17 by stitching 20. The tabs 19 are spaced apart the same distance as openings 14. At the opposite free end of tabs 19, 10 there is affixed the other half of the fastener 21 which co-acts with fastener part 15.

In order to attach fur collar 16 to the garment 15 10, tabs 19 are inserted through openings 14 and snap fasteners 21 are snapped together with complementary snap fasteners 15. The fur collar will then be snugly in position without wrinkling so that it appears to be permanently attached to the outer garment 10. It should be 20 noted as shown in Fig. 3, that one-half of the snap fastener 21 appears on tabs 19 with the male portion upward so that when tabs 19 are inserted through tabs 14, the back of the tabs 19 do not show the snap fastener. The preferred method 25 of manufacture is to use the same material for tabs 19 as that of the outer garment so that tabs 19 will barely be visible.

Instead of fur collar 16, different types of fur collars may be used or cloth collars of different 30 shapes and designs can be used by the same means of attachment; that is, by the use of tabs such as 19 spaced apart the same distance as openings 14 so that such collars can be interchanged depending upon the desires of the 35 wearer.

It is obvious that various changes and modifications may be made in the details of construction without departing from the general spirit of the invention as set forth in the appended claims.

40 I claim:

1. In combination with an outer garment having a collar permanently attached to the yoke of said garment, openings between said collar and said yoke, one-half of a snap fastener attached 45 below each of said openings with a detachable collar having tabs spaced apart the same distance as said openings, the other complementary half of said snap fastener attached to the free end of said tabs for attaching said collar to said 50 outer garment.

2. An outer garment having a short collar permanently attached to the yoke of said garment, openings between said short collar and said yoke, a detachable collar having tabs attached to the neck portion of said detachable

collar, fastening means attached to the free end of said tabs cooperating with complementary fastening means on said yoke for removably securing said detachable collar to said garment.

3. An outer garment having a yoke, a collar permanently attached to said yoke, openings spaced apart between said collar and said yoke, a detachable collar encircling said permanent collar, said detachable collar having tabs attached to the neck portion thereof, said tabs having fastening elements attached to the free ends thereof cooperating with complementary fastening elements attached to said yoke for attaching said detachable collar to said garment.

4. A garment having a yoke and a permanent collar attached to the neck portion of said yoke, small openings between said collar and said yoke, fastening elements attached to said yoke below said openings, a detachable collar for said garment having tabs attached to the inner edge of said detachable collar, said tabs being spaced apart the same distance as said openings and arranged to pass through said openings, complementary fastening elements attached to the ends of said tabs for removably securing said detachable collar by said fastening elements.

SALVATORE LAPICK.
